UNITED STATES PATENT OFFICE.

GIOVANNI B. MALDURA, OF ROME, ITALY.

BRIDGE FOR MANDOLINS.

SPECIFICATION forming part of Letters Patent No. 554,828, dated February 18, 1896.

Application filed August 13, 1895. Serial No. 559,182. (No model.)

To all whom it may concern:

Be it known that I, GIOVANNI BATTISTA MALDURA, a subject of the King of Italy, and a resident of Rome, Italy, have invented certain new and useful Improvements in Finger-Boards and Bridges for Mandolins, of which the following is a specification.

My invention relates to certain new and useful improvements in finger-boards and bridges for mandolins and mandolas, and the object of my invention is to provide such means as to obtain easier playing and the best sound.

Upon the accompanying drawings, which form a part of this specification, the same letters of reference denote corresponding parts, of which—

Figure 1 is a perspective view of the finger-board actually used in mandolins. Fig. 2 is a section of the same on line $x-x$ of Fig. 1. Fig. 3 is a perspective view of the finger-board of my system. Fig. 4 is a longitudinal section of the same. Figs. 5 and 6 are sectional views, respectively, on lines $z-z$ and $y-y$ of Fig. 3. Fig. 7 shows, in enlarged scale, the bridge as it is now used in mandolins; and Fig. 8 shows, also in enlarged scale, the new bridge of my system.

The mandolin used at present is made with straight finger-board F, Fig. 1, and bridge P, Fig. 7, parallel to the sounding-board T. As thus constructed, the instrument presents practically great defects, as will be explained.

When the wrist is worked in the execution of the tremolo (to prolong the sound, as in song) while the fore part of the right arm rests on the edge of the mandolin playing the first string E, one naturally describes the curve $a-b$, Fig. 7, with the plectrum (or pen) which is farthest above the sounding-board on the side of the basses G and falls on the cantino (or melody strings) E. The plectrum must always hurry over this same line $a-b$ to touch the strings E and develop the tremolo. However, when one wishes to touch, not the cantino E but the second strings A, the hand must necessarily deviate from the first or natural line $a-b$ and describe a second line $c-d$, while the wrist must be turned inward, from which results such rigidity that the tremolo cannot be executed with that freedom and softness with which it would be ex-

ecuted if one could move the hand to touch the strings A without thus forcing the wrist. This also happens when one has to play on the strings D and G, but in a more pronounced degree, because the deviation from the first or natural line $a-b$ is greater and the strength of the wrist is increased.

A fine tremolo results when to the rapidity and isochronism of the strokes is added the same degree of force in each; but this equality in the strokes cannot be obtained in mandolins having the bridge parallel to the sounding-board, because the plectrum (or pen) falling on the twin strings from above to below, or running over the line $a-b$ from a to b , will touch both the strings, (first and second,) and returning from below to above or running over the line from b to a will touch only one of the twin strings—that is, the second—consequently making the stroke from low to high weaker than that from high to low, a weakness that increases with the constantly-diminished impetus of the hand, and that also produces a certain disastrous loss of equilibrium. Moreover, on the first of the twin strings the plectrum in the stroke from above to below scarcely touching this string will naturally slip on the second, the latter being struck with a greater depth of plectrum and deviating more from its position of equilibrium will make ampler vibrations, developing more sound than it is possible to develop on its first string and producing inequality. This with regard to the tremolo on the single strings.

Let us see what follows when one tries to make the tremolo on three or all four strings, as in part music. Here the plectrum must not only be brought from a to g , Fig. 7, to touch the bass-strings, but it must come still farther, so that, reaching the point m , it may trace the line $m-n$ in contact with all four twin strings. To make this possible the wrist must be twisted more than if only the fourth string G were to be played, forcing the wrist-muscles to such a degree that sometimes become so painful as to seriously impede progress. The line $m-n$, traced by the plectrum to embrace the four strings, instead of one alone, must necessarily be much longer and the tremolo must be executed with much greater velocity, thus giving the wrist more

impetus, which, requiring greater force, is much more fatiguing. Observing these defects I applied myself to find another system. First of all I studied the straight bridge and raised it on the side of the basses G to the cantino E in such wise that the curve naturally traced by the plectrum lies on this line, allowing the wrist by an almost imperceptible exertion to carry the hand to any string of the instrument with the plectrum, as appears from Fig. 8. The curve *a b* is that run over by the plectrum seconded by the raising of the bridge P'.

It will be easily understood how with this new bridge it is much easier to play the four strings at the same time and how one can draw the same intensity or degree of sound from the four strings simultaneously. From this I have obtained two other advantages. First, the two strings of each sound can be struck with equal force and in both the upper and lower strokes, and, second, the bass-strings being raised farther from the sounding-board T have acquired greater depth and intensity of sound.

In consequence of this modification I have given the outline shown by Figs. 5 and 6 to the finger-board F' that the fingerling of the bass-strings may be facilitated. Next, I studied to leave the greater part of the sounding-board free, thus rendering it more resonant.

I accomplished this by vaulting (or arching) that part X Y, Figs. 3, 4 and 5, of the finger-board F' that rests on the sounding-board T, so that instead of being glued over the entire surface X W it dominates it now, only fastened by its lateral parts W W'. I also lightened the bridge by making in it elliptical openings through its center just under each pair of strings, as in Fig. 8.

Having thus described my invention, what I claim, and desire to secure by Letters Patent, is—

1. A finger-board and bridge for mandolins and mandolas higher on the side of the basses G than on the side of the cantino E so that the plane of the four strings is not parallel to the plane of the sounding-board, but is inclined toward the cantino E and the curve naturally traced by the plectrum lies in it, substantially as described.

2. In combination with a mandolin, a sounding-board, a finger-board and the bridge higher on the bass side and inclining downward to the cantino, substantially as described.

In witness whereof I have hereunto set my hand in presence of two witnesses.

G. B. MALDURA.
